UNITED STATES PATENT OFFICE.

ADOLPHE BOUCHARD, OF ST. ELMO, ALABAMA.

CORSET.

SPECIFICATION forming part of Letters Patent No. 471,597, dated March 29, 1892.

Application filed November 24, 1891. Serial No. 412,929. (No model.)

To all whom it may concern:

Be it known that I, ADOLPHE BOUCHARD, a citizen of the United States, residing at St. Elmo, in the county of Mobile and State of Alabama, have invented certain new and useful Improvements in Corsets; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention has relation to improvements in corsets; and the object is to provide a corset which will fit the person without injuring the health of the wearer and which will retain and preserve the supported parts in symmetrical and natural positions; and I accomplish the purposes of my invention by the means hereinafter described, and which I have fully and clearly illustrated in the accompanying drawings, wherein—

Figure 1 is a view showing the corset applied to the person. Fig. 2 is a front view of the corset. Fig. 3 is a detail of the respective breast-stays, and Fig. 4 is a detail of the respective vertical springs or stays.

It is the purpose of my invention, when worn by the person, to maintain the figure erect without undue lacing and to keep the busts in natural, easy, and beautiful position of separation and outward direction.

The bodice or textile portion of my improved corset is designated by A and is cut by proper measurement to fit the person by rules well known to the trade. In the meeting edges of the front are secured the usual steel stays 1, provided with clasps for locking the edges together. The bodice is also provided with the usual sheaths for taking and holding the stays. The side stays 2, located under the arms, are bent to shape so as not to press on the body except at the point coming on the waist-lines of the wearer. The front stays 3 4, arranged on the opposite fronts of the corsets, are also bent in vertical

direction to the shape of the waist and to the contour of the respective breasts which they embrace and support, having a curved 50 or rounded outward bend 6 and an inward curved or rounded bend 7 to support the breasts in their application thereto, and the intermediate side stays 5 have their upper portions bent outward, as shown in Fig. 4 of 55 the drawings. The horizontally - arranged breast-stays 8 9 10 are bent or curved to meet the curvatures of the breasts and have their ends fastened to the intermediate side stays and clasp-stays, respectively, as shown, and 60 intermediately are secured to the vertical stays 3 and 4, substantially as shown in the drawings. The stays are, as usual, of steel-spring or bone and are made light and flexible and as arranged hold the breasts so that the 65 beauty of the natural shape is presented, and to effect the correct adjustment and fit of the several stays they are bent to fit a measured model before being applied to the corset.

Having thus described my invention, what 70 I claim, and desire to secure by Letters Patent, is—

A corset comprising a body and bust portion having vertical front stays 1 and side stays 2, vertical front breast-stays 3 4, bent at 75 their upper portions outward, as at 6, and inward, as at 7, and arranged on opposite sides of the center of the bust, the intermediate side stays 5, arranged between the side stays 2 and the breast-stays 4 and bent at their upper ends to the contour of the breasts, and the elliptically-arranged cross breast-stays 8 9 10, having their ends united at a common point adjacent to the front stay 1 and to the intermediate side stays 5 and intermediately 85 secured to the bent portions of the breast-stays 3 and 4, substantially as shown and described.

In testimony whereof I affix my signature in presence of two witnesses.

A. BOUCHARD.
